UNITED STATES PATENT OFFICE.

FREDERICK A. FRERICHS, OF PHILADELPHIA, PENNSYLVANIA, ASSIGNOR TO THE HORN & BRANNEN MANUFACTURING CO., OF PHILADELPHIA, PENNSYLVANIA, A CORPORATION OF PENNSYLVANIA.

DESIGN FOR AN ELECTRIC-CANDLE WALL-SCONCE.

57,428.

Specification for Design.

Patented Mar. 29, 1921.

Application filed June 12, 1920. Serial No. 388,646. Term of patent 3½ years.

To all whom it may concern:

Be it known that I, FREDERICK A. FRERICHS, a citizen of the United States, and residing at Philadelphia, in the county of Philadelphia and State of Pennsylvania, have invented a certain new, original, and ornamental Design for an Electric-Candle Wall-Sconce, of which the following is a specification, reference being had to the accompanying drawing, forming part thereof.

The figure is a perspective view of an electric candle wall sconce, showing my new design.

I claim—

The ornamental design for an electric candle wall sconce, as shown.

FREDERICK A. FRERICHS.
